UNITED STATES PATENT OFFICE.

FRANK A. HALLECK, OF MICHIGAN CITY, INDIANA, ASSIGNOR TO SULLIVAN MACHINERY COMPANY, A CORPORATION OF MASSACHUSETTS.

DRILLING APPARATUS.

Application filed November 6, 1923. Serial No. 673,186.

My invention relates to drilling apparatus.

It has for its object to provide an improved drill, and especially one adapted to use in deep holes like oil wells. A further object of my invention is to provide an improved hydraulic drill feeding mechanism and more particularly a feeding mechanism of the character mentioned in which it is made possible to obtain a long feed without increasing the length of the feeding mechanism and while enabling the latter to be maintained relatively compact longitudinally.

In the accompanying drawings I have shown for purposes of illustration one form which my invention may assume in practice.

In the drawings,—

Fig. 1 is a front elevation of a drilling apparatus constructed in accordance with my improvement.

Fig. 2 is a side elevation of the same showing the hydraulic feeding mechanism in vertical section.

In this illustrative construction I have shown an apparatus of the general type described and claimed in my copending application Ser. No. 619,835, filed Feb. 19, 1923, the same comprising a suitable motor or engine 1 operatively connected to a reel 2 and to a rotating tubular member 3 of polygonal cross section for a rod line adapted to extend through said member 3 and be rotated thereby and to be fed by hydraulic feeding mechanism including a hydraulic cylinder 4, the hydraulic feeding mechanism being improved as hereinafter described, together with some of the connections to the rotating mechanism and the support on which the whole mechanism is carried and with which it is movable bodily relative to the hole and guides 5 carried on the machine base.

In my improved construction it will be observed that the motor 1 is connectible through a suitable clutch 6 with a bevel pinion 7 rotatable on a horizontal axis and meshing with a larger bevel gear 8 rotatable with the member 3 on a vertical axis, the members 3 and 8 being coaxially disposed and a bearing 9 being likewise coaxial therewith and above the gear 8. As shown, the cylinder 4 also carries therein a flanged

sleeve 10 suitably attached thereto at the bottom of the cylinder and herein extending therein up through the cylinder into the removable top head of the cylinder. Moreover, the piston 11 in the cylinder 4 carries a sleeve 12 of greater diameter than the sleeve 10 and fitting closely around the same. This sleeve 12 is connected at its upper end in a usual manner to the swivel head 13. The swivel head 13 specifically comprises upper and lower ball thrust bearings 11^a and 12^a, respectively, between which a collar 13^a is interposed, the collar being threadedly connected to the upper end of the rotating member 3 which carries the rod line. The sleeve or piston rod 12 is secured as by screws to the lower part of the swivel head casing. It will thus be evident that the piston 11 is operative to feed the sleeve 12, the swivel head 13, and the rotating member 3, by which the drill rods are carried, upwardly or downwardly as desired, the thrust of the rod line being absorbed by the thrust bearings 11^a and 12^a within the swivel head 13, all as well known in the art. The sleeve 12 is also packed at the top of the cylinder by a suitable packing 14 held in position on the top of the cylinder through holding means comprising a removable clamping sleeve and screws 15. As shown, the lower end of the sleeve 12 is flanged and rests on a flange 16 in the bore of the piston and is clamped thereon by a ring and screws 17. A packing 18 is also inserted between the lower end of the sleeve 12 and the outer periphery of the sleeve 10 telescopically carried thereby, this packing 18 being held in place by a clamping means including a ring and screws 19.

In the operation of my improved construction it will of course be understood that when fluid is supplied to the opposite sides of the piston in the general manner common to hydraulic feeds, the hydraulic feed will operate in its usual manner, it only being necessary to point out that during this operation the sleeves 10 and 12 will telescope in such manner as to enable the desired operation while giving a very compact construction longitudinally and avoiding any objectionable leaking between the opposite sides of the piston. As a result of my improved construction, it will be observed that it is made possible to use a

low support between the operative mechanism and the machine base and thereby eliminate the necessity for providing the relatively much higher frame described and claimed in my copending application mentioned, at the same time that it is made possible to make up the support in one piece thereby simplifying the construction. Moreover, it will be noted that by changing the 10 connections between the gears 7 and 8 a still further reduction in necessary height below the gear 7 is made possible. These and other advantages of my improved construction will, however, be clearly apparent 15 to those skilled in the art.

While I have in this application specifically described one form which my invention may assume in practice, it will be understood that this form of the same is 20 shown for purposes of illustration and that the invention may be modified and embodied in various other forms without departing from its spirit or the scope of the appended claims.

25 What I claim as new and desire to secure by Letters Patent is:

1. In a drilling apparatus, hydraulic drill rod feeding mechanism including a cylinder, telescopically arranged tubular elements extending through said cylinder, said elements having relative longitudinal movement during feeding, and a piston movable in said cylinder and secured to one of said elements.

2. In a drilling apparatus, hydraulic drill 35 rod feeding mechanism including a cylinder, telescopically arranged tubular elements having relative longitudinal movement during feeding, and a piston movable in said cylinder and secured to the outer one of said elements.

3. In a drilling apparatus, hydraulic drill rod feeding mechanism including a cylinder, telescopically arranged tubular elements having relative longitudinal movement during feeding, the inner one of said elements being stationary, and a piston movable in said cylinder and secured to the outer one of said elements.

4. In a drilling apparatus, hydraulic drill 50 rod feeding mechanisms including a cylinder, telescopically arranged elements having relative longitudinal movement during feeding, a drill rod rotating member extending through said elements, and a piston movable in said cylinder and secured to one of said elements.

5. In a drilling apparatus, hydraulic drill rod feeding mechanism including telescopic rod elements, one carried by and extending 60 into the cylinder and the other by the piston, and a rotating member by which the rod line is carried.

6. In a drilling apparatus, hydraulic drill rod feeding mechanism including telescopic 65 rod elements, one carried by and extending

through the cylinder and the other by the piston, packing means therefor, and a rotating member by which the rod line is carried.

7. In a drilling apparatus, hydraulic drill rod feeding mechanism including telescopic 70 rod elements, one carried by and extending through the cylinder and the other by the piston, packing means therefor including a packing between said telescopic elements and carried on the piston, and a rotating member 75 by which the rod line is carried.

8. In a drilling apparatus, hydraulic drill rod feeding mechanism including telescopic rod elements, one of said elements being carried by and extending into the cylinder 80 and being substantially the same length thereof and the other being carried by the piston, and a rotating member by which the rod line is carried.

9. In a drilling apparatus, hydraulic drill rod feeding mechanism including telescopic rod elements, the internal element being carried by and extending into the cylinder and the external element carried by the piston, and a rotating member by which the rod 85 line is carried.

10. In a drilling apparatus, hydraulic drill rod feeding mechanism including telescopic rod elements, the internal element being carried by and extending into the cylinder 95 and the external element carried by the piston, packing means for said elements, and a rotating member by which the rod line is carried.

11. In a drilling apparatus, hydraulic 100 rod feeding mechanism including a cylinder and telescopic rod elements extending through said cylinder, packing means for said elements including packing around the outer element carried on the cylinder and packing between the two elements carried by the piston, and a rotating member by which the rod line is carried.

12. In a drilling apparatus, hydraulic 105 rod feeding mechanism including relatively movable telescopic members, and rotating mechanism below the same extending into one of the telescoping elements and having a driving bevel gear and a driven bevel gear disposed above said driving gear 110 and coaxial with said telescopic members.

13. In a drilling apparatus, hydraulic 115 rod feeding mechanism including a cylinder, telescopically arranged elements having relative longitudinal movement during feeding, and rotating mechanism below said feeding mechanism including a rotating member by which the rod line is carried, said member extending through said elements and cylinder and having a driving bevel gear and a driven bevel gear disposed above said driving gear and coaxial with said telescopic elements.

14. In a drilling apparatus, the combination with a hydraulic drill rod feeding mech- 120

- anism including a cylinder, a piston in said cylinder, and a swivel head, of a piston rod extending upwardly from the cylinder and connected to the swivel head, a sleeve secured 5 in stationary relation with respect to the cylinder and extending therethrough, a tubular member carried by the swivel head and extending through said sleeve and the piston and to which the drill rods are adapted to be connected and through which the 10 drill rods are adapted to extend, and means for rotating said member disposed below the hydraulic cylinder.
15. In a drilling apparatus, the combination with a hydraulic drill rod feeding mechanism including a cylinder, a piston reciprocable in said cylinder, and a swivel head, of a piston rod extending upwardly from the cylinder and connected to the swivel head,
20. a sleeve secured in stationary relation with respect to the cylinder and extending upwardly through the piston, a stuffing box carried by the cylinder through which said piston rod extends, a member carried by the 25 swivel head and extending through said sleeve and said piston rod and to which the drill rods are adapted to be connected, and means for rotating the drill rods disposed below the hydraulic cylinder.
30. 16. In a drilling apparatus, the combination with a hydraulic drill rod feeding mechanism including a cylinder having upper and lower heads, a piston reciprocable in said cylinder, and a swivel head, of a piston 35 rod extending upwardly through the upper cylinder head and connected to the swivel head, a sleeve secured to the lower cylinder head and extending upwardly through the piston, and a stuffing box carried by the upper cylinder head through which said piston rod is adapted to extend.
40. 17. In a drilling apparatus, the combination with a hydraulic drill rod feeding mechanism including a cylinder having upper and lower heads, a piston reciprocable in said cylinder, and a swivel head, of a piston rod extending upwardly through the upper cylinder head and connected to the swivel head, a sleeve secured to the lower cylinder head 45 and extending upwardly through the piston, and stuffing boxes carried by the upper cylinder head and the piston through which said rod and said sleeve, respectively, are adapted to extend.
55. 18. In a drilling apparatus, the combination with a hydraulic drill rod feeding mechanism including a cylinder having upper and lower heads, a piston reciprocable in said cylinder, and a swivel head, of a stuffing box 60 carried by the upper cylinder head, a piston rod extending upwardly through said stuffing box and connected to the swivel head, a stuffing box carried by the piston, and a sleeve secured in stationary relation with respect to the cylinder extending through said
- last mentioned stuffing box and telescopically arranged within said piston rod.
19. In a drilling apparatus, the combination with a hydraulic drill rod feeding mechanism including a cylinder having upper and lower heads, a piston reciprocable in said cylinder, and a swivel head, of a stuffing box carried by the upper cylinder head, a piston rod extending upwardly through said stuffing box and connected to the swivel head, 70 a stuffing box carried by the piston, a sleeve secured in stationary relation with respect to the cylinder extending through said last mentioned stuffing box and telescopically arranged within said piston rod, and a member carried by the swivel head extending downwardly through said piston rod and said sleeve and to which the drill rods are adapted to be connected.
20. In a drilling apparatus, the combination with a hydraulic drill rod feeding mechanism including a cylinder having upper and lower heads, a piston reciprocable in said cylinder, and a swivel head, of a stuffing box carried by the upper cylinder head, 75 a piston rod extending upwardly through said stuffing box and connected to the swivel head, a stuffing box carried by the piston, a sleeve secured in stationary relation with respect to the cylinder extending through said last mentioned stuffing box and telescopically arranged within said piston rod, and a member carried by the swivel head extending downwardly through said piston rod and said sleeve and to which the drill rods are adapted to be connected.
21. In a drilling apparatus, the combination with a hydraulic drill rod feeding mechanism including a cylinder having upper and lower heads, a piston reciprocable in said cylinder, and a swivel head, of a stuffing box carried by the upper cylinder head, a piston rod extending upwardly through said stuffing box and connected to the swivel head, 80 a stuffing box carried by the piston, and a sleeve secured to the lower cylinder head and extending upwardly through said last mentioned stuffing box to a point adjacent the upper cylinder head and telescopically arranged within said piston rod.
22. In a drilling apparatus, the combination with a hydraulic drill rod feeding mechanism including a cylinder having upper and lower heads, a piston in said cylinder, and a swivel head, of a piston rod extending upwardly through the upper head of the cylinder and connected to the swivel head, a sleeve secured to the lower cylinder head and extending upwardly through the piston, a stuffing box carried by the upper cylinder head, and means for rotating the 90 drill rods disposed below the hydraulic cylinder.
- 100
- 105
- 110
- 115
- 120
- 125
- 130

23. In a drilling apparatus, the combination with a hydraulic drill rod feeding mechanism including a cylinder having upper and lower heads, a piston reciprocable in said cylinder, and a swivel head, of a piston rod disposed coaxially with the drill rods and extending upwardly through the upper cylinder head and connected to the swivel head,

a sleeve secured to the lower head and extending upwardly through the piston, a ¹⁰ stuffing box carried by the upper head, and means for rotating the drill rods disposed below the hydraulic cylinder.

In testimony whereof I affix my signature.

FRANK A. HALLECK.
